No. 800,147.

PATENTED SEPT. 26, 1905.

E. M. GREENBAUM.
GAS BURNER.
APPLICATION FILED DEG. 5, 1904.

UNITED STATES PATENT OFFICE.

EDGAR M. GREENBAUM, OF NEW YORK, N. Y.

GAS-BURNER.

No. 800,147.

Specification of Letters Patent.

Patented Sept. 26, 1905.

Application filed December 5, 1904. Serial No. 235,427.

To all whom it may concern:

Be it known that I, EDGAR M. GREENBAUM, a citizen of the United States, residing at 1485 Fifth avenue, in the city, county, and State 5 of New York, have invented a new and useful Improvement in Gas-Burners, of which the following is a specification.

My invention relates to an improvement in bases for Bunsen and incandescent gas burners, and has for its objects, first, a simple construction for regulating the burner without the use of any extraneous article to accomplish this purpose, and, second, to afford a simple "by-pass" wherein the gas is not entirely shut off even when the regulating cap 15 or nipple is closed down to its limit.

The accompanying drawings, which form part of this specification, show, in—

Figure 1, a sectional side view through lines 20 X X of Fig. 2. Fig. 2 is a plan view of Fig. 1 through lines O O, the vertical dot-and-dash line showing the adjustable cap removed to the right of said line, so as to expose the shoulder of the base and the conoidal stud.

Fig. 3 is a front view of the thumb-wheel or 25 pinion for operating the adjustable cap, the Bunsen tube being broken away; and Fig. 4 is a central sectional view of a modification for attaching the pinion-wheel to the Bunsen 30 tube.

Similar characters of reference indicate similar parts in the several views.

The base has the usual female thread 1 to screw on a fixture, and a male thread 2, upon 35 which the Bunsen tube 3 is screwed.

4 is the perforated air-hole, of which there are usually a plurality in said tube.

5 is a male projection provided with a thread 6.

40 7 represents perforations in the shoulder 8. 9 is a conoidal stud.

10 is an adjustable cap provided with a thread 11 of the same size and pitch as the male thread 6. This cap has a central hole 45 12, which, with the stud 9, regulates the quantity of gas. On the periphery of said cap there are longitudinal ribs or teeth 13. To make this cap cheaply, I prefer to use "pinion" or gear rod, working the same in a turret- 50 lathe, as in this manner it can be finished in one operation.

14 is a pinion or thumb wheel, whose teeth 15 mesh with the teeth of the cap. This wheel is also made of gear-rod, and is held in oper-

ative position on the tube in any preferred 55 manner. In Figs. 1, 2, and 3 I show it on a wire 16, which acts as a bearing. The wire is pushed up into a series of inwardly-projecting straps 17, which are drawn from the metal of the Bunsen tube, the tube being 60 pierced at 18 for permitting the thumb-wheel 14 to project some distance beyond it.

In Fig. 4 I show a modification for supporting the thumb-wheel by means of a staple 19, which is riveted or secured to the tube 65 above and below the said wheel.

20 is an indentation on the conoidal stud for the purpose of permitting a slight escape of gas when the cap 10 is screwed down, thus forming a simple "by-pass," so called. It is 70 obvious that instead of this means of providing a by-pass the hole 11 of the cap may have a notch in the wall, or the stud 9 may be drilled through centrally, as is usual in this class of bases; but I prefer to groove or indent the 75 stud, as it is the cheapest and most practical way of obtaining the desired results.

When a by-pass is not desired, the notching or drilling is avoided.

Such being the construction of my improved 80 base, the operation is as follows: When the parts are assembled, as shown in Fig. 1, to regulate the supply of gas to the burner the pinion or thumb wheel 14 is revolved, the serrated surface preventing the finger from slipping. The rotation of this wheel causes the 85 adjustable cap 10 to turn on the male thread, and thereby be raised or lowered, the hole 12 acting with the stud in cutting off or increasing the supply without reducing the pressure. 90 When arranged as a by-pass, the cap is screwed down by means of the thumb-wheel to its full limit, the small escape of gas through the groove 20 maintaining a jet in the burner, so it can be turned on full without relighting it. 95 This is a desirable feature, as the greatest damage to an incandescent mantle is usually done when first lighting the burner. The gas and air are almost invariably in an explosive mixture and the concussion resulting from 100 such lighting is destructive to the chemical ashes of which the mantle is composed.

Nearly all the parts of my improved base can be cheaply made on a monitor or turret lathe, and by reason of the adjustable cap being entirely within the circumference of a Bunsen tube it can be made of a very small diameter. Hence little stock or weight of metal 105

is used, and by reason of its being manipulated by a thumb-wheel, which is always ready for operation, no screw-driver, hair-pin, pencil, or other article foreign to the burner is used.

The several parts can be easily taken apart and cleaned without any tool being required.

Such being my invention, what I desire to secure by Letters Patent is—

- 20 1. In a base for Bunsen and similar burners, the base, provided with a superimposed adjustable cap having peripheral teeth, said cap being actuated by a pinion-wheel pivotally supported by said burner, the teeth of said cap meshing with those of said pinion, substantially as described.
- 15 2. In a base for Bunsen tubes, an adjustable cap rotatively mounted on said base, said cap being entirely within the circumference of
- 20 said tube, in combination with a pinion-wheel supported by said tube, the periphery of said

wheel extending beyond the periphery of said tube, substantially as described.

3. In a base for Bunsen and similar burners, a base provided with an upwardly-extending male thread, a conoidal stud supported on a shoulder, perforations through said shoulder, a superimposed adjustable cap rotatively mounted on said male thread, said cap having peripheral longitudinal teeth, in combination 25 with a pinion-wheel whose teeth mesh with the teeth of said cap, and means for supporting said pinion-wheel in contact with said cap, substantially as described.

In testimony whereof I have signed my name 30 to this specification, in the presence of two subscribing witnesses, this 1st day of December, 1904.

EDGAR M. GREENBAUM.
